UNITED STATES PATENT OFFICE.

JOHN NEWARK, OF CORAL, PENNSYLVANIA.

COAL-DIGGER.

1,368,189.

Specification of Letters Patent.

Patented Feb. 8, 1921.

Application filed June 26, 1918. Serial No. 242,035.

To all whom it may concern:

Be it known that I, JOHN NEWARK, a citizen of the United States, residing at Coral, in the county of Indiana and State 5 of Pennsylvania, have invented new and useful Improvements in Coal-Diggers, of which the following is a specification.

This invention relates to new and useful improvements in coal diggers and the principal object of the invention is to provide 10 means for under-cutting the shaft head.

Another object of the invention is to provide means for boring a hole in the shaft head and then automatically moving the bit 15 transversely across the head to form the under-cut.

Other objects of the invention relate to the means for adjustably supporting the 20 boring means on a truck so that the cutting tool may be placed in the desired position in the shaft head, to means for feeding the tool forwardly to bore a hole in the head, to means for automatically stopping this forward movement when the hole is completed, 25 to means for moving the cutting tool side-wise after the completion of the forward movement, to means for returning the parts to starting position, and to means for giving the parts a slow forward movement and 30 a quick return movement.

The invention also consists in certain other features of construction and in the combination and arrangement of the several parts, to be hereinafter fully described, 35 illustrated in the accompanying drawings and specifically pointed out in the appended claims.

In describing my invention in detail, reference will be had to the accompanying 40 drawings wherein like characters denote like or corresponding parts throughout the several views, and in which:—

Figure 1 is a side elevation of the invention.

Fig. 2 is a plan view.

Fig. 3 is an end view.

Fig. 4 is a plan view, with parts broken away, of the means for moving the device cross-wise.

Fig. 5 is a longitudinal section.

Fig. 6 is a section on line 6—6 of Fig. 4. Figs. 7, 8, 9 and 10 are detailed views.

In these views 1 indicates a truck upon 55 which the device is mounted. The device is adjustably mounted on said truck by means of an arm 2 having one end rotatably se-

cured to the truck and its other end rotatably supporting a block or guide member 3. 4 indicates the lower track member, of substantially channel form and provided with 60 the guide ways 5 into which the block or guide member 3 fits. The outer sides of this track member are provided with the guide pieces 6. One side of this track member is provided with the rack 7 and on the opposite 65 side the guide piece 6 has the rack 8 on its upper edge.

9 indicates the lower carriage engaging with the lower track member and having its sides embracing the sides of said member. 70 These sides of the carriage are provided with suitable grooves for receiving the guide pieces 6 so as to hold the carriage on the track. The upper side of the carriage is provided with an enlarged circular stud 10 which engages a circular opening 11 formed in the bottom of an upper track member 12. The stud forms a bearing for a toothed wheel 13 which is engaged by a toothed wheel 14 located on a shaft 15 carried by the 80 arms 16 projecting from one side of the lower carriage 9. The wheel 14 is loosely mounted on said shaft and said wheel is provided with interior teeth 17 which are adapted to be engaged by dogs 18 carried by a 85 disk 19 keyed to the shaft 15. These dogs are so arranged that they will lock the wheel 14 to the disk when said wheel is rotated in one direction and will slip over the teeth when the wheel is rotated in the other direction so that the disk will not be moved. 90 20 indicates a toothed wheel keyed to the shaft 15 and meshing with the rack 7 on the lower track member 4.

The other side of the carriage 9 carries a 95 pair of toothed wheels, which are indicated by the numerals 21 and 22. The wheel 21 carries the dogs 23 which are adapted to engage the teeth 24 on the wheel 22 when said wheel 21 is rotated in one direction, and 100 to slide over said teeth when the wheel is rotated in the other direction. The wheel 22 meshes with the rack 8 on the track member 4 while the wheel 21 engages with teeth 25 formed on the under face of the wheel 13. 105

The upper track member 12 is of channel form and is rotatably secured to the lower carriage 9 by means of the stud 10 and opening 11 as before described. The bottom of the track member is provided with a longitudinally extending slot 26 and the sides of said member are provided with the lon- 110

itudinally extending grooves 27. These sides, below said grooves are provided with the racks 28, one of which is of greater length than the other for a purpose to be 5 hereinafter described.

29 indicates the upper carriage slidably mounted in the upper track member and having the ribs 29⁷ engaging the grooves 27. The forward end of the carriage carries 10 the cutting tool 30. This tool is of the well-known worm type, with the edges of the worm provided with the teeth 31⁷. These teeth engage sockets formed in the edges 15 of the worm and are removably held in said sockets by the set screws 31⁸. Thus the tool will bore a hole and will also cut transversely when moved sidewise. The tool is rotated by means of the beveled gear 31 thereon meshing with a like gear 32, which is keyed 20 to a shaft 33 journaled in the upper carriage 29. The said shaft is provided with a crank 34 to which the crank shaft 35 of the motor 36 is connected. The motor is of any desired type and is mounted on the rear end 25 of the carriage as shown. The shaft 33 is provided with the worm 37 and a gear 38 on a longitudinally extending shaft 39 meshes with this worm. The shaft 39 is suitably journaled in the lower part of 30 the carriage 29 and carries a large bevel gear 40 and a small gear 41. The large gear 40 meshes with a bevel gear 42 on a stub shaft 43 carried by the carriage and extending through the slot 26 in the bottom 35 of the member 12 and the lower end of this shaft carries a toothed wheel 44. A part 45 of the carriage projects through the said slot 26 and forms a bearing for the lower end of the shaft. This wheel 44 meshes with the 40 wheel 13 carried by the stud on the lower carriage when the carriage is in its forward position.

The rear end of the carriage carries a shaft 46. The outer ends of this shaft 45 carry toothed wheels or gears 48 and 49 which mesh with the racks 28 on the upper track member 12. The shaft 46 is provided with the double sliding gears 50, operated by a suitable lever 51 so that said gears 50 50 may be moved into mesh with the gears 40 and 41. By this means, when the cutting tool is moved forward to bore a hole in the shaft head one of the gears 50 is moved into mesh with the small gear 41, while the other 55 gear 50 is moved out of mesh with the large gear 40. This will cause the gear 48 on the shaft 46 to travel over the short rack 28 and thus slowly feed the carriage forward to cause the cutting tool to bore a hole in 60 the shaft head. This movement will continue until the gear 48 runs off the end of the rack 28 and stops the carriage. When this occurs the gear 44 on the stub shaft 43 will be in mesh with the gear wheel 13 carried 65 by the lower carriage. When the lever

51 is moved in the opposite direction to shift the gears 50 to their other positions the gear 49 will be connected with the large gear 40 so that the upper carriage will be quickly returned to its rearmost position.

When the gear 44 on the stub shaft 43 is in mesh with the gear 13, said gear 13 will be caused to rotate and the rotation of this gear will, through the gears 21 and 22 and dogs 23 before described, cause the lower carriage to slowly move along the lower track member to cause the cutting tool to make a transverse cut in the shaft head.

Before beginning the boring operation the machine is placed with the lower track member 4 parallel with the shaft head and with the upper track member at right angles to the lower track member and with its front end facing the shaft head so that the boring tool will be in position to bore a hole in the shaft head. The engine is then started to move the upper carriage forwardly to cause the boring tool to bore a hole in the shaft head and when the carriage reaches the end of its forward movement the gear 44 will engage the gear 13 so that the lower carriage will move along the lower trackway so as to make a transverse cut in the shaft as before described.

I form an opening 60 in the block 3 and a plurality of openings 61 in the lower track member so that the track member may be held against movement on said block 3 by placing a bar or rod through said openings 61 and 60. This will prevent the track member 4 from moving on said block 3 when the lower carriage is moved. Similar bars and holes or set screws may be provided for preventing rotation of the part 2 in the truck and the rotation of block 3 in the part 2.

When the lower carriage reaches the end of the lower track member said carriage is held against movement in any suitable manner, such as by placing a timber against the shaft head with its end resting against said carriage. The bar passing through the holes 60 and 61 is then removed and the engine reversed. This will cause the wheel 13 to be rotated in an opposite direction so that the dogs 23 carried by the wheel 21 will slip over the teeth on the wheel 22 while the dogs 18 will engage the teeth on the wheel 14 so as to rotate the toothed wheel 20. This will cause the lower track member 4 to quickly slide on the block 3 and through the lower carriage 9, said carriage being held stationary as before described. As soon as the said track member has reached the desired position the engine is stopped and the bar again placed through the holes 60 and 61 and the carriage 9 released. The said carriage 9 is then ready to travel along the lower track member 4. In this way a transverse cut may be made in the shaft head substantially twice the length of the track member 4.

When the lower carriage reaches the end of the lower track way it may be returned to its starting position on said track way by reversing the engine as before described, but 5 permitting the bar to remain in the holes 60 and 61. After the cut is made the parts may be rotated on the truck and the truck withdrawn from the shaft.

It is thought from the foregoing description that the advantages and novel features of my invention will be readily apparent.

I desire it to be understood that I may make changes in the construction and in the combination and arrangement of the several 15 parts, provided that such changes fall within the scope of the appended claims.

What I claim is:-

1. A coal-digger comprising a truck, a lower track member adjustably mounted 20 thereon, a pair of racks on said member, a lower carriage slidably mounted on said track member, two sets of gearing carried by the carriage and engaging said racks, pawls for connecting the gears of each set 25 together, a main gear on the carriage connected with the two sets of gearings, an upper track member adjustably carried by the carriage, racks on said upper track member, an upper carriage slidably mounted on said 30 upper track member, gears carried by said upper carriage engaging with said racks, a motor on the carriage connected with said gears for moving the upper carriage on its track, means for automatically connecting 35 said motor with the main gear on the lower carriage at the end of the forward movement of the upper carriage, and a cutting tool carried by the upper carriage and operatively connected with the motor.

40 2. A coal-digger comprising a truck, a lower track member adjustably mounted thereon, a pair of racks on said member, a lower carriage slidably mounted on said track member, two sets of gearing carried

by the carriage and engaging said racks, 45 pawls for connecting the gears of each set together, a main gear on the carriage connected with the two sets of gearings, an upper track adjustably carried by the carriage, a pair of racks on said upper track member, 50 one of said last named racks being longer than the other, an upper carriage slidably mounted on the upper track member, toothed wheels carried by the upper carriage and engaging said pair of racks, slideable gears 55 connected with said wheels, driven gears with which the sliding gears are adapted to engage, a motor connected with said driven gears and carried by the upper carriage, a stub shaft carried by the upper carriage, a 60 gear on the upper end of said shaft engaging with the driven gears connected with the motor, a gear on the lower end of said shaft for engaging with the gearing on the lower carriage at the end of the forward movement 65 of the upper carriage and a boring tool carried by the upper carriage and connected with the motor.

3. A coal digger comprising a truck, a lower track member, means for adjustably 70 mounting said track member on the truck, a lower carriage, means for slowly moving the carriage on said track member in one direction and quickly moving it in the opposite direction, an upper track member carried 75 by the lower carriage, an upper carriage carried by the upper track member, means for slowly moving the carriage forwardly on said upper track member and quickly returning said carriage to its rearmost position, a cutting tool carried by the carriage and means cooperating with the before mentioned means for automatically moving the lower carriage in its feeding direction at 80 the completion of the forward movement of the upper carriage.

In testimony whereof I affix my signature.
JOHN NEWARK.
